UNITED STATES PATENT OFFICE.

WILLIAM B. LEONARD, OF CHICAGO, ILLINOIS.

CHAIR FOR REINFORCING-RODS FOR REINFORCED CONCRETE.

1,343,326.

Specification of Letters Patent. Patented June 15, 1920.

Application filed June 26, 1919. Serial No. 306,857.

To all whom it may concern:

Be it known that I, WILLIAM B. LEONARD, a citizen of the United States, residing at Chicago, in the county of Cook and State of Illinois, have invented a new and useful Chair for Reinforcing-Rods for Reinforced Concrete, of which the following is a specification.

The object of my invention is to produce a simple, efficient chair for the metallic reinforcing bars commonly used in reinforced concrete, the device being of such character that it may be cheaply produced; readily placed by unskilled labor; and serve to definitely retain either single or double courses of rods in proper positions, preliminary to the pouring of the concrete, the construction being such that portions left exposed on the removal of the forms, may be readily removed.

The accompanying drawings illustrate my invention. Figure 1 is a perspective view of a fragment of a form supporting a plurality of reinforcing rods, with my improved chairs in place, some holding single rods and others holding crossing rods; Fig. 2 a side elevation showing the chair in final form when holding crossing rods; and Fig. 3 a side elevation, showing the chair when holding a single rod.

The chair is formed from a single piece of wire as follows: An entry tip 10, a stop shoulder 11 substantially at right angles to tip 10, a standard 12, a U-shaped seat 13 and an inverted leg 14. The seat 13 is formed, as shown in Fig. 2, by bending the wire back upon itself adjacent standard 12. The standard 12 is preferably of a height somewhat greater than the height of the upper surface of the lower reinforcing rods 15, so that the seat 13 is somewhat deeper than the diameter of rod 15. The inverted leg 14 is of such length that, when the chair is used to support and retain a second reinforcing rod 16 lying upon rod 15, the leg can be bent down around rod 16 and preferably reach to the form board 17, or perhaps enter it slightly, although this is not absolutely essential.

The standard 12 may be either substantially at right angles to stop 11, as shown in Fig. 2, or may be at an angle thereto, as shown in Fig. 3. It is a little more con-

venient, as will appear, to have the standard 12 substantially at right angles to stop 11 and 55 to then bend the standard to one side or the other, if desired, after the chair has been driven to place in the form.

In operation, the chair is readily driven, like a nail, into place at the desired position relative to the form and reinforcing rods 15 placed in the seats thereof, said seats holding them securely against displacement, not only laterally but also at a proper height above the forms so that they will be thoroughly embedded in the concrete. If only a single series of reinforcing rods is to be supported at that particular point, a portion of the length of the inverted leg 14 may, if desired, be clipped off and the leg then bent 60 around the bar 15, as shown in Fig. 3, being preferably turned around and down far enough to bring its end either against, or 65 slightly into, the form 17, so as to thus form a foot which will prevent downward displacement of the rod during that period of erection when workmen are necessarily tramping over the rods preliminary to, and 70 during the pouring of the concrete.

If a second series of rods 16 is to be placed, 80 they are laid upon and transversely of, the rods 15 and against the upper ends of standards 12, as well as against the U-shaped seats 13. The inverted legs 14 are then bent down around rod 16 and the end preferably 85 brought against, or slightly into, the form 17, as illustrated in Fig. 2; thus bracing the rods and chair against downward displacement.

I have found in practice that the chair can 90 be produced very cheaply; that it is readily put in place by comparatively unskilled labor; and that it firmly retains the reinforcing rods in proper place.

I claim as my invention:

1. As an article of manufacture, a chair for reinforcing rods, consisting of a single piece of wire bent to form an entry tip 10, a stop portion 11, a standard 12, a U-shaped seat 13, and an inverted leg 14, substantially 100 as described.

2. As an article of manufacture, a chair for reinforcing rods, comprising an entry tip, a U-shaped seat, having a depth greater than the rod to be supported, and a flexible 105 upper portion normally arranged to leave

the seat free of access and adapted to be bent downwardly and around a rod lying transversely to the seat.

3. As an article of manufacture, a chair for reinforcing rods, comprising an entry tip, a U-shaped seat, and a flexible upper portion normally arranged to leave the seat

free of access and adapted to be bent downwardly and around a rod lying transversely to the seat.

10

In witness whereof, I have hereunto set my hand at Chicago, Illinois.

WILLIAM B. LEONARD.
